UNITED STATES PATENT OFFICE

2,213,948

FLUID PRESSURE ACTUATED MOTOR

Herbert C. Bowen, Detroit, Mich., assignor to Hydraulic Brake Company, Detroit, Mich., a corporation of California

Application December 5, 1938, Serial No. 244,080

7 Claims. (Cl. 60—54.6)

This invention relates to brakes, and more particularly to fluid pressure means for actuating brakes.

Broadly the invention comprehends a fluid pressure actuated motor operative to actuate brakes in two phases, initially at low fluid pressure, and thereafter at relatively high fluid pressure without proportionately greater applied operating force.

10 An object of the invention is to provide a fluid pressure actuated motor operative in two phases.

Another object of the invention is to provide a fluid pressure actuated motor including low pressure actuated means, high pressure actuated means, and pressure actuated means for rendering the low pressure means ineffective during operation of the high pressure means.

Other objects and advantages of the invention 20 will appear from the following description taken in connection with the drawing forming a part of this specification, and in which—

Fig. 1 is a vertical sectional view of a brake taken just back of the head of the drum, illustrating the invention as applied; and

Fig. 2 is a sectional view substantially on line 2—2, Fig. 1.

Referring to the drawing for more specific details of the invention, 10 represents a fixed support or backing plate adapted to be secured to an axle or to an axle housing, and associated with the backing plate is a rotatable drum 12 adapted to be secured to a wheel.

The backing plate has suitably arranged thereon a pair of spaced anchors 14 and 16 and a pair of adjustable retractile stops 18 and 20. A pair of corresponding friction elements or shoes 22 and 24 have their articulate ends pivoted on the anchors 14 and 16, and their force applying ends normally rest on the adjustable stops 18 and 20. The shoes are of conventional type, each including a web 26 supporting a rim 28 having secured thereto a friction lining 30 suitable for cooperation with the drum.

45 A compound fluid pressure actuated motor 32 slidably mounted on the backing plate is connected as by thrust pins 34 and 36 to the force applying ends of the shoes, and a retractile spring 38 connecting the shoes adjacent their force applying end serves to return the shoes upon completion of a braking operation to their retracted positions on the stops 18 and 20.

The motor 32 includes a cylinder 40 having a small chamber 42 and a relatively large chamber 44 communicating with one another as by a

passage 46 concentrically disposed with relation to both chambers. An inlet passage 48 adapted to be connected as by a conduit 50 to a suitable source of fluid pressure communicates with the passage 46, and a passage 52 providing a communication between the intake passage 48 and the large chamber 44 is controlled as by a check valve 54.

The end of the passage 46 opening into the chamber 44 is enlarged to provide an annular shoulder, and seated on this shoulder is an annular washer 56. A shell 58 threaded in the enlarged end of the passage clamps the annular washer on its seat. This shell extends well into the chamber 44, and the free end thereof is closed as by a head 60 provided with a port 62, and suitably arranged in the wall of the shell is a port 64 providing a communication between the interior of the shell and the chamber 44.

10 A piston 66 reciprocable in the shell 58 is seated on a heavy spring 68 interposed between the back of the piston and the head of the shell. A rod 70 is mounted concentrically in the head of the piston, and a sealing cup 72 seated on the head of the piston embraces the rod. The rod 25 extends through the shell, the annular washer 56, and the passage 46 into the small chamber 42, and a valve 74 is carried by the rod for control of the communication between the passage 46 and the shell. The valve 74 is normally held 30 on a flexible seat 76 supported on the annular washer 56. The rod also has thereon within the chamber 42 a valve 78 adapted to seat on a flexible washer 80 on the bottom of the chamber 42.

35 A piston 82 reciprocable in the chamber 42 has on its head a sealing cup 84. A light spring 86 interposed between the cup 84 and the washer 80 serves to retain the cup and washer 80 against displacement. The piston 82 also has a flange 40 87 adapted to abut the cylinder when the piston is at rest so as to fix the retracted position thereof, and arranged in the back of the piston is a recess 88 for the reception of the thrust pin 34, and a dust shield 90 connects the thrust pin 45 to the open end of the chamber 42.

A piston 92 reciprocable in the chamber 44 has a concentric recess 94 receiving the shell 58, and a port 96 in the bottom of the recess opens to the atmosphere. The piston 92 has on 50 its head an annular sealing cup 98 embracing the wall of the chamber 44 and the shell 58, and the cup is held against displacement by a spring 100 interposed between the cup and the bottom of the chamber. The piston 92 also has in its back 55

a recess 102 receiving the thrust pin 36, and a dust shield 104 is connected between the thrust pin 36 and the open end of the chamber 44.

In the normal operation, fluid under pressure enters the passage 48, thence passes through the passage 46, past the valve 78, into the chamber 42, resulting in an increase of pressure on the fluid in the chamber 42 and consequent movement of the piston 82 and the cylinder 40 in opposite directions. This movement of the piston and the cylinder effectively moves the shoes 22 and 24 into engagement with the drum 12.

Upon attaining a predetermined pressure on the fluid, the valve 74 cracks and admits fluid under pressure into the shell 58, thence through the port 64, into the chamber 44. As the pressure on the fluid in the shell 58 and the chamber 44 builds up, the valve 78 moves to its seat and closes off communication between the chamber 42 and the passage 46. This results in trapping fluid in the chamber 42 and thereafter the pressure on the fluid acting on the piston 66 and on the head of the valve 78 maintains the valve 78 closed while the pressure on the fluid in the chamber 44 acting on the piston 92 causes further movement of the piston 92 and movement of the cylinder 40 in the opposite direction, resulting in applying the shoes with increased force and less effort on the part of the operator.

30 Upon concluding a braking operation, pressure on the fluid is released, whereupon the valve 74 is urged to its seat by the spring 68, and the valve 78 opens to establish communication between the chamber 42 and the passage 46. This results in opening the chamber 42 directly to the inlet passage 48, and return of the fluid from the chamber 42 to the source of supply, and the fluid in the chamber 44 is displaced therefrom past the check valve 54 to the source of supply.

40 While this invention has been described in connection with certain specific embodiments, the principle involved is susceptible of numerous other applications that will readily occur to persons skilled in the art. The invention is, therefore, to be limited only as indicated by the scope of the appended claims.

Having thus described the various features of the invention, what I claim as new and desire to secure by Letters Patent is:

50 1. A fluid pressure actuated motor comprising a floating cylinder having a small chamber and a relatively large chamber arranged in spaced relation to one another, a passage connecting the chambers and an intake port communicating with the passage, a piston reciprocable in each of the chambers, and a double end valve in the passage normally open to establish communication between the small chamber and the passage and to close communication between the large chamber and the passage and operative under a predetermined pressure to close communication between the small chamber and the passage so as to trap fluid in the small chamber and to establish communication between the large chamber and the passage.

65 2. A fluid pressure actuated motor comprising a floating cylinder having a small chamber and a relatively large chamber, a passage connecting the chambers and an inlet port communicating with the passage, a piston reciprocable in each of the chambers, and valve mechanism in the passage operative upon attaining a predetermined pressure to close communication between the small chamber and the passage so as to trap fluid

in the small chamber and to establish communication between the large chamber and the passage.

3. A fluid pressure actuated motor comprising a shiftably mounted cylinder having a small chamber and a relatively large chamber, a passage connecting the chambers and a fluid inlet communicating with the passage, a piston reciprocable in each of the chambers, and a fluid pressure actuated valve for control of the passage operative upon attaining a predetermined pressure to close communication between the small chamber and the passage so as to trap fluid in the small chamber and to establish communication between the large chamber and the passage.

4. A fluid pressure actuated motor comprising a shiftably mounted cylinder having a small chamber and a relatively large chamber, a passage connecting the chambers and an intake port communicating with the passage, a controlled passage between the intake port and the large chamber, a piston reciprocable in each of the chambers, and a fluid pressure actuated valve for control of the passage connecting the chambers operative upon attaining a predetermined pressure to close communication between the small chamber and the passage so as to trap fluid in the small chamber and to establish communication between the large chamber and the passage.

5. A fluid pressure actuated motor comprising a shiftably mounted cylinder having a small chamber and a relatively large chamber and a passage connecting the chambers, an intake passage communicating with the passage connecting the chambers, a controlled passage connecting the intake passage to the large chamber, a piston reciprocable in each of the chambers, and a spring-pressed fluid actuated double-end valve for control of the passage connecting the chambers operative upon attaining a predetermined pressure to close the small chamber and open the large chamber.

6. A fluid pressure actuated motor comprising a floating cylinder including a small chamber, a relatively large chamber arranged in spaced concentric relation to the small chamber, a passage connecting the chambers, a fluid inlet communicating with the passage and a controlled passage connecting the inlet with the large chamber, a piston reciprocable in each of the chambers, a double-end valve in the passage having a part subjected to the initial pressure on the fluid in the motor tending to close communication between the small chamber and the passage and to establish communication between the large chamber and the passage, and another part subjected to pressure on the fluid in the small chamber upon closing the communication between the small chamber and the passage.

7. A fluid pressure actuated motor comprising a floating cylinder having a small chamber, a relatively large chamber, a passage connecting the chambers, a fluid inlet communicating with the passage and a controlled passage connecting the inlet to the large chamber, a piston reciprocable in each of the chambers, a double-end valve in the passage for control of communication between the small and large chambers with the passage, and a spring-pressed piston attached to the valve and arranged in concentric relation to the piston complementary to the large chamber and exposed to pressure in the large chamber.
